UNITED STATES PATENT OFFICE.

DON D. MYERS, OF TOLEDO, OHIO, ASSIGNOR TO MONROE AUTO EQUIPMENT MFG. CO., OF MONROE, MICHIGAN, A CORPORATION OF MICHIGAN.

PUMP BASE.

Application filed July 26, 1926. Serial No. 124,924

This invention relates to reciprocating pumps.

This invention has utility when incorporated in cylinder base and features of air type of reciprocating pumps as used for inflating pneumatic tires of vehicles.

Referring to the drawings:

Fig. 1 is a side elevation of an embodiment of the invention in a hand operated 10 tire pump;

Fig. 2 is a section on the line II—II, Fig. 1, looking in the direction of the arrow;

Fig. 3 is a section on the line III—III, Fig. 2, looking in the direction of the arrow; 15 and

Fig. 4 is a section on the line IV—IV, Fig. 3, looking in the direction of the arrow.

Pump cylinder 1 is shown as having piston 2 therein from which upwardly extends piston rod 3 through cylinder head 4 to operating handle 5.

A base is herein provided comprising a pair of tread portions 6 having therebetween upwardly extending boss 7. This boss 7 is offset or slightly eccentric to the line between the pair of treads 6. Centrally between the pair of treads 6, but eccentrically disposed as to the boss 7, is upwardly extending flange 8. This base member is of sheet metal and is 30 shown as of greater length than width.

The flange 8 provides on its inner side a first seat for embracing the cylinder 1. This cylinder 1 as extending through opening provided by the flange 8, terminates toward 35 the boss 7 with a flare portion 9 thus snugly holding the cylinder 1 in position as to seat 10 on the inner side of the flange 8. The boss 7, on its inner side, provides a seat 11 into which is thrust cup-shaped cylinder head 40 having cup bottom 12 and flange of cup side portion 13 as a ring flange seating in the seat 11. This cylinder head cup 12, 13, as disposed in the seat 11 of the boss 7, has the cup

bottom or diaphragm 12 about the flare portion of the cylinder 1 stiffening the action of 45 the seat 10, as well as supplementing the sealing relation of this head as to the bottom of the cylinder 1. This cylinder head diaphragm 12 is shown as having way or channel 14 therefrom extending radially under a 50 portion of the flare 9 to the eccentric portion of the boss 7 as laterally of the flange 8 where this channel 14 is in communication with upwardly extending port 15 herein shown as carrying fitting 16, with which coupling 17 55 may coact in connecting flexible duct 18 as extending to tire valve fitting 19. This assembly of the two-part cup cylinder head and the tread portion, may be snug press fit assembly as a light weight rigid structure. 60 The tread portion 6 may be reinforced by corrugations 20 with the depending flange 21 therefrom. This flange 21 may have struck-up portions 22 to engage the lower side of the flange 13 of the cylinder head as additional 65 holding means in anchoring the parts in the set-up or assembled relation of this stamped or pressed base structure.

What is claimed and it is desired to secure by United States Letters Patent is:— 70

A pump base including an extended tread portion, a hollow boss rising from said base, a cup-shaped cylinder head mounted in said boss and possessing a depression in the upper surface thereof, an outlet passage located at 75 the outer end of said boss and in communication with the cylinder head depression, a pump cylinder eccentrically mounted in said boss, the lower portion of said cylinder having a flared end so as to be positioned in said 80 boss, said cylinder head and boss serving as locking means to retain said pump cylinder, and retaining means integral with the base to position the cylinder head within said boss.

In witness whereof I affix my signature.
DON D. MYERS.
